UNITED STATES PATENT OFFICE

ARTHUR MAGEE, OF ST. PETERSBURG, FLORIDA

LURE FOR USE IN DOG RACING OR COURSING

Application filed May 2, 1930. Serial No. 449,190.

This invention relates to lures for use in dog racing or coursing; and an object is to provide an improved device for supporting and operating the lure along the track or course.

Another object of the invention is to provide an improved device for supporting and operating a lure, comprising a carriage constructed and designed to operate along a track and provided with means cooperating with an upper rail or track to prevent derailment of the carriage, and also provided with means projecting laterally from the carriage for supporting and operating a lure. By this construction, I am enabled to operate the lure carriage along a track or guide at one side of the course and thus avoid the necessity of constructing the track below the surface of the ground or in a tunnel, which largely increases the cost of the installation without any compensating advantage. On the contrary, by my present construction, I avoid the increased cost required in installations embodying subterranean tunnels and, in addition, my entire construction is easily accessible above the ground, so that any changes, alterations or repairs can easily be made.

Another object of the invention is to provide an improved device of the character and for the purpose mentioned possessing the several advantageous features of construction and operation herein disclosed, reference being made to the accompanying drawings, in which—

Fig. 1 is a plan view of a preferred embodiment of the invention.

Fig. 2 is a side elevation.

Fig. 3 is a front elevation.

Fig. 4 is a rear elevation.

The carriage which supports and operates the lure is constructed and arranged to operate upon and along a lower guide or rail forming a channel and comprising a bottom wall 1 and upwardly extended flanges 2 integral or rigid with said wall 1. There is a

cooperating rail or guide of similar construction comprising a top wall 3 having along its edges depending flanges 4. The rail 3 is electrically energized and constitutes a circuit device which, in practice, is shielded or guarded or protected by appropriate means (not shown).

The carriage comprises a pair of frame members 5 supported at their forward ends on an axle 6 to which a pair of wheels 7 and 8 are attached. The rear ends of the frame members 5 are attached to a motor frame 9. The rear end of the motor frame 9 is attached to a bracket 10 supported on an axle 11 on the ends of which the rotary traction wheels 12 are mounted.

The wheels 7 and 8 operate between and adjacent to the flanges 2 and upon the wall 1. The flanges 2 serve as guides to prevent the carriage from leaving the track. The wheels 12 also operate between the flanges 2 and upon the wall 1 and are spaced apart approximately the same distance as are the wheels 7 and 8.

The motor shaft 13 has attached to its front end a pinion 14 which meshes with a pinion 15 on the axle 6. Thus, when the motor 16 is running, the wheels 7 and 8 are positively rotated and the carriage is propelled along the track 1—2, which is arranged at one side of the race course or track.

The motor frame 9 has attached thereto a plate 17 from which two pairs of arms 18 project upwardly and have vertical slots 19 near their upper ends. A pair of axles 20 have their ends projecting through the slots 19 in each pair of arms 18, and each axle 20 supports an inverted cup-like spring seat 21. Coil springs 22 have their upper ends engaging in the spring seats 21 and their lower ends engaging in spring seats 23 attached to the plate 17. Wheels or rollers 24 are mounted on the axles 20 and operate against the plate 3 between the flanges 4. The springs 22 hold the wheels 24 yieldingly against the track and also press the carriage downwardly upon the

track 1. These springs 22 will yield to any irregularities in the track so as to permit the carriage to operate properly irrespective of such irregularities. The electric current passes from the track 3 through the rollers 24 and thence through the remaining metallic elements to the motor, which is grounded on the track 1. Thus the motor will be operated whenever the track 3 is energized.

10 A socket 25 is attached to one of the frame members 5, and a similar socket 26 is attached to the motor frame 9. These sockets 25 and 26 support a pair of converging arms 27 the inner ends of which are connected by a bracket 28 having a socket 29 in connection therewith. The socket 29 is designed and intended to receive the post 30 which supports the lure 31. A clamping device 32 is supported by the socket 29 and is operative to clamp and to release the post 30 so as to hold the lure in rigid position in connection with the socket 29 or to permit removal and replacement of the lure, as desired.

25 The arms 27 are connected by a bolt 33 having thereon between said arms 27 a spacing tube 34 for said arms. The ends of the arms 27 which are in the sockets 25 and 26 are engaged by clamps 35 which may be tightened to hold the arms in rigid connection with the carriage, or released to permit removal and replacement of the arms, as desired. The arms may be removed by bending them slightly as they are withdrawn from the sockets 25 and 26. The arms 27 may be made 35 with a sufficient degree of resiliency to oscillate the lure when the carriage is in motion, so as to obtain a more natural effect.

40 This device may be constructed and installed without great cost, and may be used as an amusement device and for the purpose of training racing dogs. The construction and arrangement of the device may be varied within equivalent limits without departure from the nature and principle of the invention. I do not restrict myself unessentially, but what I claim and desire to secure by Letters Patent is:—

45 1. A device of the character described comprising a carriage frame, wheels supporting the front and rear ends of said frame respectively, a pair of converging sockets attached respectively to the front and rear portions of the frame and projecting laterally therefrom, a pair of outwardly converging resilient arms having their inner ends engaged in said sockets, means detachably securing the ends of said arms in said sockets, a socket device attached to the outer ends of said arms, and means for supporting a lure in connection 55 with said socket device.

60 2. A device of the character described comprising a carriage frame, wheels supporting the front and rear ends of said frame respectively, a pair of converging sockets attached 65 to the front and rear end portions of said

frame and projecting laterally therefrom, a pair of outwardly converging resilient arms having their inner ends engaged in said sockets, said arms being arranged to oscillate vertically automatically and as an incident to 70 the travel of the device, and a detachable element for supporting a lure in connection with the outer ends of said arms for oscillation thereby.
